UNITED STATES PATENT OFFICE.

J PEARL WILSON, OF JACKSONVILLE, FLORIDA.

FINGER-BAR.

1,315,891.

Specification of Letters Patent.

Patented Sept. 9, 1919.

Application filed May 13, 1915, Serial No 27,919. Renewed February 13, 1919. Serial No. 278,865.

To all whom it may concern:
Be it known that I, J PEARL WILSON, citizen of the United States, residing at Jacksonville, in the county of Duval and State of Florida, have invented certain new and useful Improvements in Finger-Bars, of which the following is a specification.

My invention relates to an improvement in finger-bars for feeding battens to be used in the manufacture of wire-bound boxes and crates, and this bar is extensible in order to make it adaptable to boxes of different lengths, and is adapted to be used in connection with fingers secured thereto, each of which engage a batten one at a time, forcing it from the bottom of the hopper into position on the veneer preparatory to its being secured thereto, after which the bar is automatically released and returns to a position to move forward another set of battens, and so on.

In the accompanying drawings:—

Figure 1 is a view in side elevation;

Fig. 2 is a plan view;

Fig. 3 is an end view;

Fig. 4 is a fragmentary detail view of the lug-releasing mechanism;

Fig. 5 is a modified form of clamping means permitting adjustment of the finger-bars and of the fingers with respect to said bars:

Fig. 6 is a top plan view of the same;

Fig. 7 is an end view of the same; and

Fig. 8 is a view of an adjustable stop with a resilient bumper mounted therein, being engaged by one end of the finger-bar.

The finger-bar 1 is extensible and is preferably composed of three sections, namely a central section 1, and two end sections 2, 2. These are provided with slots 3, 3, extending longitudinally thereof, and the bolts 4, 4, with nuts 5 thereon hold the finger-bar in its lengthened or shortened adjustment.

The fingers 6, 6, three being shown, although the number might, of course, be varied, are securely bolted as at 7, 7, to the finger-bar. These fingers extend forwardly and are each provided with a lug 8, adapted to extend through an opening in the front of the batten-hopper 9, whereby each finger is adapted to engage and move forward a single batten 30 from the hopper bottom at a time.

The ends of the two outer finger-bars rest and slide upon the upper edge of the T-irons 10, 10, of the frame, as shown in Fig.

3, the butt ends 11, 11, of the outer fingers engaging the inner faces of the T-irons which form guides therefor, preventing endwise movement of the finger-bar, while permitting it to move in the direction of the length of the fingers.

The veneer-slats 12, 12 rest at their ends upon the inwardly-extending flanges 13, 13, of the T-irons, as shown in Fig. 3, and these slats are fed forwardly beneath the battens, as shown in Fig. 1, by the lugs 14, 15, 16, 17 and 18 on the endless chains 19, 19, of which there are two in the machine illustrated, the chain traveling through channels 20, 20, 70 provided therefor, which channels also provide an intermediate support beneath the veneer-slats.

At intervals, a lug is higher than the rest, as at 15', so as to travel in the path of a trip 21 extending downwardly from the finger-bar, as shown in Figs. 1, 3 and 4, thus carrying the finger-bar with the fingers forward through the openings in the bottoms of the hoppers to remove a batten from each hopper and leave them in position transversely upon the veneer slats, ready to be stapled or otherwise secured thereto. This movement of the finger-bar continues until the roller 22 on the trip rides up upon the wedge-shaped projection 23 fastened to the hopper, which by engaging the roller lifts the trip, as shown in Fig. 4, against the action of the springs 24, 24 on either side thereof, removing the trip from the path of the lug 15', which latter continues on, whereupon the finger-bar is automatically returned to its normal position by the spiral springs 25, 25.

In the construction hitherto described, the fingers are bolted rigidly to the finger-bar. It is perfectly possible to adjust these in two ways, namely along the finger-bar to bring them nearer together, and also lengthwise to shorten the fingers as shown in Figs. 5, 6 and 7, in which a clamp 25' embraces the finger-bar and fingers at their point of intersection, the fingers passing through the slots 26, 26, in the opposite sides of the clamp, and the screws 27, 27, being provided to hold them rigidly in their adjusted position.

It should be mentioned that one at least of the T-rails 10 of the frame is adjustable, and can be moved to any position desired within the width of the stapling machine being used. Ordinarily one T-rail is stationary. When desired to make a wider or narrower

box-web, the adjustable T-rail is set to the width desired. Thus the distance between T-rails is adjustable, as well as the length of the finger-bar. Likewise the distance between the sections of the hopper is adjustable. In fact the machine is adapted for making a box anywhere from a foot to five feet in length, as well as any dimension between these two extreme points. The distance between the endless feed-chains always remains the same as to the respective side or T-rails.

The stops 28, 28, are secured to the T-rails by screws 29, 29, to limit the backward movement of the finger-bar when pulled back by the springs 25, 25.

In Fig. 8, a stop 28 is disclosed as having a resilient bumper 30 mounted in one side thereof, adapted to be engaged by one end of the finger-bar 2 for taking up the shock of its return to its normal position.

I claim:

1. The combination with a slidable finger-bar having fingers thereon, and a trip connected with the finger-bar, of a movable device having means thereon at intervals which engages the trip and moves the finger-bar and fingers a predetermined distance, means for automatically disengaging the trip, and means for automatically retracting the finger-bar to its normal position.

2. In a machine for feeding slats and battens, the combination with a hopper having a tapering projection, and an endless chain carrying lugs thereon of different lengths, said lugs being in position to feed the slats, of a finger-bar, a spring-actuated trip connected with the finger-bar and in position normally to be engaged by one of the lugs, the arrangement being such that the finger-bar is fed forward with the movement of the

chain until it reaches the projection on the hopper, said projection operating to automatically disengage the trip from the lug on the chain, and means to automatically return 45 the finger bar to its normal position.

3. In a machine for feeding slats and battens, the combination with a slidable finger-bar carrying fingers and trips, of endless chains carrying lugs which feed the slats to form a box or crate, certain lugs being arranged to move in the path of the trips to carry the finger-bar forward and cause the fingers to feed forward a batten, means for automatically releasing the trip, and means 55 for returning the finger-bar to its normal position.

4. In a machine for feeding slats and battens, the combination with an extensible finger-bar, fingers carried by the bar, trips on the finger-bar, moving-devices having lugs for feeding the slats, certain of said lugs being arranged to move in the path of the trips on the finger-bar to carry the latter forward and cause a batten to be fed forward by the fingers, and means for automatically returning the finger-bar to its normal position.

5. In a machine for feeding slats and battens, the combination with a finger-bar, fingers adjustably secured to the finger-bar, trips on the finger-bar, moving-devices having lugs for feeding the slats, certain of said lugs being arranged to move in the path of the trips on the finger-bar to carry the latter forward and cause a batten to be fed forward by the fingers, and means for automatically returning the finger-bar to its normal position.

In testimony whereof I affix my signature. 80

J PEARL WILSON.
